UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 34,737, dated July 2, 1901.

Application filed June 6, 1901. Serial No. 63,473. Term of patent 7 years.

To all whom it may concern:

Be it known that I, WILLIAM T. SMITH, a citizen of the United States, residing in Philadelphia, Pennsylvania, have invented and produced a certain new and original Design for a Woven Fabric, of which the following is a specification.

My design is shown in the accompanying drawing, which represents sufficient of the pattern to illustrate the design, the remainder being simply a repetition of what is shown.

The pattern is of a geometrical character, and comprises a series of figures 1, 2, 3, 4, 5, and 6, contained within a border 7. The figures each have a central ornament 9 in a field which is surrounded by bordering bands 10, 11, and 12 of step-like character. The figures 2 and 3 are each composed of squares touching at the corners. The figures 4 are of a triangular character, with tooth-like projections

at the sides. The figure 5 is composed of a pair of triangular figures disposed base to base, and the figure 6 consists of four triangles disposed base to base and has outer members composed of parallel lines, and the border 7 has inwardly-projecting rectangular members 13.

Having thus described my invention, I claim and desire to secure by Letters Patent—

The design for a woven fabric, substantially as described and as shown in the accompanying drawing.

In testimony whereof I have signed my name to this specification in the presence of two subscribing witnesses.

WILLIAM T. SMITH.
